Atty.

UNITED STATES PATENT OFFICE.

JOHN BLOOM, OF ROCKFORD, ILLINOIS.

SAFETY-RAZOR.

1,304,734.

Specification of Letters Patent. Patented May 27, 1919.

Application filed June 26, 1918. Serial No. 241,915.

To all whom it may concern:

Be it known that I, JOHN BLOOM, a citizen of the United States, residing at Rockford, in the county of Winnebago and State of Illinois, have invented certain new and useful Improvements in Safety-Razors, of which the following is a specification.

The primary object of this invention is to provide a generally improved and simplified safety razor designed so that the shaving operation may be performed the same as with an ordinary razor as distinguished from the operation of those safety razors which have a handle fixed in angular relation to the blade and impose the difficulty of keeping the blade at the proper angle while shaving.

In furtherance of this general object, I have provided a safety razor characterized by a tubular handle shaped at one end to form a holder and guard pickets for a double edge blade, and a clamping member movable longitudinally within the handle for clamping the blade to the holder.

Other objects and attendant advantages will be appreciated as the invention becomes better understood by reference to the following description when considered in connection with the accompanying drawings, in which—

Figure 1 is a face view of a safety razor illustrating one embodiment of my improvements;

Fig. 2, a side view thereof;

Fig. 3, a longitudinal sectional view through the razor taken substantially on the line 3—3 of Fig. 1;

Fig. 4, a detail face view of the blade detached;

Fig. 5, an end view of the blade;

Fig. 6, a cross-sectional view taken on the line 6—6 of Fig. 2;

Fig. 7, a side view of a modified form of my invention;

Fig. 8, an end view of Fig. 7; and

Fig. 9, a perspective view of one of the blades, of which two are used in the form of razor shown in Fig. 7.

Referring to Figs. 1 to 6 of the drawings, it will be noted that the handle and blade holder or backing are integrally formed, preferably from a piece of tubing cut away at one side to provide the requisite guard pickets for the blade. In both embodiments of my improvements, the tubular piece 10 constitutes the handle, and one end thereof

is cut away on one side, as shown, providing a holder or backing 11 having longitudinal sides shaped to provide guard pickets 12. This holder, substantially semi-circular in cross section, is adapted to receive on its inner side a blade designated by character 13, specially designed for fitting within the curved holder. The blade, also semi-circular in cross-section, has opposed sharpened edges 14 coöperating with the guard pickets 12 and is adapted to be clamped to the holder or backing 11 by a member which will be presently described. To hold the blade in position against sidewise and lengthwise displacement the blade is provided at each end with a notch or recess 15, which receives the fixed lugs or stops 16 when the blade is properly positioned on the holder.

The clamping member or rod, designated generally by reference character 17, for securing the blade to the holder, is permanently associated with the handle and adjusted into and out of clamping position, preferably by a thumb nut 18 threaded onto the end of the rod which projects through the lower end of the handle. The clamping rod extends longitudinally through the handle 10 and is equipped at the inner side of the holder with a ball clamping head 19 adapted to engage the inner side of the blade about medially between the ends thereof and to be drawn tight against the blade for clamping the same to the holder. This clamping action is effected by drawing the rod lengthwise into engagement with an inclined surface 21 on the handle. This inclined surface, in the present instance, is in the form of a tapered opening in a wall 22 at the base of the blade holder, the hole being eccentric with respect to the handle and disposed closer to the blade holder 11. The clamping rod is provided with an annular tapered face 23 coöperating with the tapered surface 21 so that when the thumb nut 18 is tightened against the end 24, the ball end 19 of the rod will be drawn by the action of the inclined surfaces 21 and 23 into engagement with the blade 13 to clamp the same to the holder. An expansion spring 25 on the rod 17 intermediate the end 24 of the handle and an abutment 26, constantly urges the rod lengthwise in a direction to withdraw the surface 21, so that when the thumb nut 18 is unscrewed the clamping head 19 will be automatically withdrawn from the blade, permitting the same to be

easily removed from the holder. Suitable means is provided for limiting lengthwise movement of the clamping rod, and in the present instance, consists of a set screw 27 5 in the end 24 of the handle engaged in a slot in the rod.

In use it will be readily seen that by reason of the peculiar arrangement of the blade with respect to the handle, the razor 10 may be conveniently held to position the blade at any desired angle and by simply rolling the handle between the fingers this angle may be instantly varied. Because of the arrangement of the blade in the longitudinal 15 plane of the handle, the razor may be manipulated with the handle close to the face and at an angle corresponding with the desired angle of the blade as distinguished from the inconvenient manner in 20 which a safety razor must be operated when the handle is positioned at right angles to the blade. The blade may be quickly and easily removed from the holder and clamped again in position as will be obvious, since 25 the blade-clamping means is operated solely by a thumb nut 18.

In Figs. 7, 8 and 9, I have illustrated another form of my improvements, differing chiefly in the blade construction. In this 30 form two flat blades are employed, each having a single cutting edge instead of a single curved blade having double cutting edges. The flat blades 33, each having a single cutting edge 34, are adapted to be 35 clamped by the ball head 19 of a clamping member 17 against a backing 11 suitably shaped to hold the blades in suitable angular relation as shown in Fig. 8. In order to prevent displacement of the blades and to 40 secure them in proper relation on the backing 11, each blade is provided with an opening 35, preferably countersunk, in which the ball end 19 is adapted to engage. It will be manifest when the clamping member is 45 tightened in the manner described with reference to the first embodiment, a pair of flat blades 33 will be rigidly clamped and held in fixed position on the blade holder, that upon loosening the nut 18 the blades 50 may be removed for cleaning and sharpening.

It is believed that the foregoing conveys a clear understanding of my improvements, and it should be understood that various 55 changes might be made in the construction and arrangement without departing from the spirit and scope of the invention as expressed in the appended claims.

I claim:

60 1. A safety razor comprising a handle having a blade holder, a blade, a clamping member movable longitudinally within the handle and overlapping the blade holder and adapted to clamp an interposed blade 65 to the holder, a spring for constantly urging

the clamping member in a direction to retract the same, and manually operable means for forcing the clamping member in the opposite direction for clamping the blade to the holder and for positively holding the 70 blade in such clamping position.

2. In a safety razor, a handle having formed integrally therewith a blade holder V-shape in cross section, a flat blade adapted to be positioned on each inner flat side of 75 said blade holder with the cutting edge of the blade adjacent to the outer edge of the holder and the back edge of the blade near the bend of the holder, a member disposed between the inclined sides of the V-shaped 80 holder and adapted to clamp both blades thereto, and means for moving said member to clamp the blades.

3. In a safety razor, the combination of a tubular handle having formed integrally 85 therewith at one end a V-shaped blade holder, a pair of blades each of which is adapted to be seated on one of the inclined inner sides of said blade holder, a member extending longitudinally within the tubular 90 handle and having a clamping end overlapping the V-shaped blade holder and shaped for engaging both blades and for simultaneously pressing them against the inclined sides of the holder, and means in coöperation 95 with the handle for moving said clamping member lengthwise within the handle for securing the blades in position.

4. In a safety razor, the combination of a tubular handle having a blade holder at one 100 end and a transverse wall between the tubular handle portion and blade holder portion, said transverse wall having a longitudinal opening therein formed with an inclined surface, a blade, a clamping member extending 105 from within the handle through said opening and overlapping the blade holder for clamping a blade thereto and being in co-operative relation with said inclined surface to effect a blade-clamping movement, and 110 means for moving the clamping member to clamp the blade to the holder.

5. In a safety razor, the combination of a tubular handle having at one end a blade holder, V-shape in cross section, a blade positioned on each inclined inner side of the blade holder, a transverse wall in the tubular member adjacent to the juncture of the blade holder and the tubular portion of the handle and having an opening therethrough 120 and an inclined surface, a clamping member extending through the tubular handle and beyond both ends thereof, said member being in co-operative relation with both blades at one end and being threaded at its opposite 125 end and coöperating intermediate its ends with said inclined surface, and a member engaging said threaded portion and adapted by rotation to move the clamping member lengthwise to clamp the blades against the 130

holder by reason of movement imposed by said inclined surface.

6. In a safety razor, the combination of a tubular handle having formed integrally therewith a V-shaped blade holder, the apex of which is in proximity to the periphery of the tubular handle and the inclined sides of which extend toward and to opposite sides of the longitudinal axis of said tubular handle portion, one or more blades po-

sitioned on the inner sides of said inclined sides of the holder, and a single clamping member disposed substantially co-axially within the tubular handle and having an end extending over and unattached to the inclined inner sides of the blade holder, and means for moving said member to clamp an interposed blade or blades to the inclined sides of the blade holder. 15

JOHN BLOOM.
